HEATER

Coy C. Goodrich, San Francisco, Calif.

Application February 20, 1939, Serial No. 257,403

13 Claims. (Cl. 122—356)

The present invention relates to improvements in heaters and its principal object is to provide a heater for water or other liquids that is extremely economic in the use of fuel, particularly efficient in absorbing a maximum of heat units from the products of combustion of the heating means, is adapted for use in relatively small units and is made to heat water in desired quantities almost instantaneously.

My heater is particularly adapted for use in restaurants or similar establishments where it is desirable to have boiling water available at an instant's notice, as for preparing coffee or other hot drinks, although the invention may be applied to many different uses.

More particularly it is proposed to provide a heater in which the source of heat, such as a gas flame, or the products of combustion rising therefrom, are not permitted to act on the water container itself directly, but are made to pass through a large number of fins which absorb the heat and pass it on to the container. This not only causes a better and more exhaustive heat transfer, but also prevents over-heating of the container in spots and the formation of lime at those spots.

It is further proposed to provide a construction whereby the products of combustion, after the extreme heat has thus been absorbed by the fins, are diverted and guided to pass around at least a portion of the container and between a large plurality of fins connected to the container for the transfer of additional heat units.

It is further proposed to provide a structure particularly adapted to the method of heat transfer outlined and to provide a simple unit which is economic in space and may be readily used wherever it is desired to heat water or other liquids with the greatest efficiency.

Further and other objects and advantages of my invention will appear as the specification proceeds.

The preferred forms of my invention are illustrated in the accompanying drawings in which:

Figure 1 shows a top plan view of the preferred form of the invention,

Figure 2, a side elevation of the same,

Figure 3, a bottom plan view of the same,

Figure 4, a section taken along line 4—4 of Figure 2,

Figure 5, a top plan view of a modified form of my invention, and

Figure 6, a section taken along line 6—6 of Figure 5.

While I have shown only the preferred forms of my invention, I wish to have it understood that

various changes or modifications may be made within the scope of the claims hereto attached without departing from the spirit of the invention.

In its preferred form my heater 1 comprises 5 a tubular container 2 bent into U-shape to provide two spaced and parallel legs 3 and 4, interconnected as at 5 and adapted for connection to a suitable source of liquid supply, as at 6.

The two legs are interconnected by a large 10 plurality of fins 7, preferably made of copper and arranged in parallel relation and sufficiently close to absorb substantially all the heat units from products of combustion made to pass therebetween in the manner hereinafter set forth. 15

While I do not wish to confine myself to any particular dimensions, I might state, by way of example, that in the preferred form used by me the fins are made of relatively thin sheet metal and are spaced approximately three-sixteenths of 20 an inch apart.

One of the fins appears in full view in Figure 4 and is shown as an elongated, substantially rectangular plate having two spaced, semi-circular recesses 8 in the upper edge thereof, the recesses 25 serving as seats for the tube legs and being provided with flanges 9 by means of which they are soldered or otherwise secured to the tube legs so as to be in intimate heat exchange relation therewith.

The lower corners of each fin may be turned at right angles, as shown at 10 in Figure 6, or small sections may be similarly bent out of the plane of the sheet, as at 11 in Figure 4, to provide spacing tongues for holding the fins in properly spaced relation.

It will be noted that there is considerable spacing between the tube legs and that the fins extend clear across the spacing and possibly slightly beyond the tube legs on either side thereof.

In the form shown in Figures 1—4 a large tubular container 12 is super-imposed upon the fins above the space between the tube legs, this container being considerably larger in diameter than the tube legs and being disposed considerably 45 higher than the tube legs so as to provide a large effective heat absorbing area for the fins underneath the container 12.

This container 12 serves as a reservoir for the water or liquid that has passed through the tube 50 legs and is connected to the outlet end of the U-shaped tube, as at 13. Water may be withdrawn from this container through any suitable outlet indicated at 14.

The drawings show the container 12 as being 55

- slightly spaced from the tube legs at 15, but this spacing should be such as to be negligible as an outlet for the products of combustion, and as a matter of fact, the large container is intended to form a roof or hood over the space between the tube legs so as to provide a dead pocket, which causes products of combustion rising from the burner 16 to be diverted and to pass underneath and around the lower faces of the tube legs.
10. The burner 16 may be of any suitable construction and is shown in its preferred form as a tube extending lengthwise underneath the space between the tube legs 3 and 4 and through the full length thereof. It is centrally located with respect to the spacing between the tube legs and is formed with a central lengthwise slot 17 in its upper face to discharge a ribbon flame which takes a relatively small amount of air from the surrounding atmosphere.
15. In operation, the products of combustion rise into the spaces between the fins, without first coming in direct contact with the legs of the tube. They are finely subdivided by the fins and the latter immediately absorb the major portion of the heat units carried by the products of combustion and convey the same to the tube legs for heating the water therein.
20. After the extreme heat has thus been absorbed, the products of combustion are divided in the dead pocket formed by the superimposed container 12 and pass laterally between the fins and underneath and around the bottom faces of the tube legs to the outside.
25. The absorption of heat units from the products of combustion by the fins in my apparatus is practically perfect and exhaustive. A person may place his hand near the sides of the ribbon flame or into the exhaust gases and hardly feel the effect of heat.
30. The water in the tube legs and the superimposed reservoir heats to a boiling point almost instantaneously. With suitable thermostat control, when a kettle of boiling water is withdrawn from the reservoir, it takes only a few seconds for the burner to reheat the water to boiling temperature.
35. Where a suitable hood is provided above the apparatus for endwise discharge of the exhaust gases, the latter emanate in the form of steam vapor at a temperature of approximately 140° F., although the water in the container is boiling and has a temperature of 212° F.
40. The form shown in Figures 5 and 6 differs from that hereinbefore described insofar as the upper reservoir has been omitted and a mere roof plate 18 has been substituted to cover the space between the tube legs 3 and 4, the latter being relied on for forming a dead pocket in the upper region of the fins and for diverting the gases to pass underneath and around the bottom faces of the tube legs. In this form the water enters at one end 19 of the tube and may be withdrawn at the other end, as at 20.
45. I claim:
1. In a liquid heater, a container for holding liquid and having fins thereon, means for directing a flame to pass between the fins for heating the latter in advance of the body of the container, the path of the flame being off-set relative to the body of the container, whereby the flame is prevented from directly striking the body of the container and means for guiding the products of combustion to pass around a portion

of the container body after the extreme heat has been absorbed by the fins.

2. In a liquid heater, a horizontally disposed tubular container for holding a liquid and having transverse fins projecting laterally therefrom and means for directing a flame to pass between the fins without directly striking the body of the container.

3. In a liquid heater, a horizontally disposed tubular container for holding a liquid and having transverse fins projecting laterally and downwardly therefrom, means for directing a flame to pass between the lateral fin sections without directly striking the container body and means for guiding the products of combustion to there- after pass around the lower body portion of the container and between the downwardly presented fin sections.

4. In a liquid heater, a pair of tubular liquid containers arranged in spaced and parallel relation, a plurality of fins connecting the containers and extending across the spacing between the containers, and a roof over said spacing extending substantially from one tube to the other.

5. In a liquid heater, a pair of tubular liquid containers arranged in spaced and parallel relation, a plurality of fins connecting the containers and extending across the spacing therebetween and means for directing a flame to rise in the spacing without the flame directly striking the containers.

6. In a liquid heater, a pair of tubular liquid containers arranged in spaced and parallel relation, a plurality of fins connecting the containers and extending across the spacing therebetween, means for directing a flame to cause its products of combustion to first rise through the spacing without the flame directly striking the containers, and a roof being provided above said spacing to cause the products of combustion to be diverted and to pass around the bottom faces of the containers, the fins being extended to project below the bottom faces of the containers.

7. In a liquid heater, a pair of tubular liquid containers arranged in spaced and parallel relation, a plurality of fins connecting the containers and extending across the spacing therebetween, means for directing a flame to cause its products of combustion to first rise through the spacing without the flame directly striking the containers, and a roof being provided above said spacing to cause the products of combustion to be diverted and to pass around the bottom faces of the containers, the fins being extended to project below the bottom faces of the containers and the roof comprising a tubular reservoir for the heated liquid having communication with the containers.

8. In a liquid heater, a pair of tubes arranged in spaced and parallel relation, a third tube overlying the spacing between the said tubes and substantially contacting with the latter to form a roof between said pair of tubes, and a series of transverse fins projecting downwardly from the pair of tubes and connecting the same with the third tube.

9. In a liquid heater, a plurality of fins arranged in spaced and parallel relation and having registering semi-circular seats disposed on opposite sides of the central vertical plane of the assembled fins, liquid containing tubes disposed in said seats and means for directing a flame to pass between the fins along said central plane and between the tubes.

10. In a liquid heater, a tube turned upon itself

5 to present two spaced and parallel legs, means for passing a liquid through the tube, a third tube overlying the spacing between the said legs and substantially contacting with the latter to form a roof between said legs and being connected to the outlet of the first tube, means for 10 directing a flame to pass between the legs and means interposed between the legs and the third tube for absorbing heat units from the products of combustion and for conveying the heat to the tubes.

11. In a liquid heater, a pair of substantially horizontally-disposed liquid containers arranged in spaced and parallel relation, a plurality of 15 spaced fins connecting the containers and extending across the spacing therebetween, and a burner mounted beneath the fins and paralleling the containers, the burner being made to direct a ribbon-like flame against the fins substantially 20 along the central vertical plane between the containers, whereby direct contact of the flame with the containers is prevented.

12. In a liquid heater, a pair of substantially horizontally-disposed liquid containers arranged 25 in spaced and parallel relation, a plurality of

spaced fins connecting the containers and extending across the spacing therebetween, a burner mounted beneath the fins and paralleling the containers, the burner being made to direct a ribbon-like flame against the fins substantially along the central vertical plane between the containers, whereby direct contact of the flame with the containers is prevented, and a roof overlying the fins and bridging the space substantially from one container to the other. 10

13. In a liquid heater, a pair of substantially horizontally-disposed liquid containers arranged in spaced and parallel relation, a plurality of 15 spaced fins connecting the containers and extending across the spacing therebetween, a burner mounted beneath the fins and paralleling the containers, the burner being made to direct a ribbon-like flame against the fins substantially along the central vertical plane between the containers, whereby direct contact of the flame with 20 the containers is prevented, and a roof overlying the fins and bridging the space substantially from one container to the other, the roof being supported on the tops of the fins. 25

COY C. GOODRICH. 25
